Patented July 15, 1924.

1,501,160

UNITED STATES PATENT OFFICE.

GUSTAVE M. BOREN, OF CHICAGO, ILLINOIS.

CONNECTER FOR ELECTRIC WIRES.

Application filed March 17, 1922. Serial No. 544,426.

To all whom it may concern:

Be it known that I, GUSTAVE M. BOREN, a citizen of the United States, residing at Chicago, in the county of Cook and State of Illinois, have invented certain new and useful Improvements in Connecters for Electric Wires, of which the following is a specification.

The invention relates to connectors for electric wires and is more particularly directed to connectors for connecting a service wire to the terminal posts in a fuse box.

The primary object of the invention is to provide a connector for temporarily connecting a service wire with the terminal posts of the insulating block in a fuse box that may be readily and easily attached to the fuse box for forming such connection, and readily and easily removed from the fuse box when it is wished to break or discontinue the temporary connection.

A further object of the invention is to provide an efficient, safe and inexpensive device for such purposes.

Other objects of the invention will appear from the following specification taken together with the accompanying drawings, forming a part of the specification, and in which the preferred embodiment of the invention is depicted.

In the drawings, Fig. 1 is a front elevation view of a fuse box with the door thereof thrown open showing an insulating block and the invention affixed to the fuse box.

Fig. 2 is a side elevation view similar to Fig. 1 with the side wall of the fuse box removed.

Fig. 3 is an elevation view of the service wire supporting arm.

Fig. 4 is an end view of the service wire supporting arm.

Fig. 5 is an enlarged detail view of the service wire supporting arm in contact with the binding posts, a portion of the supporting arm being broken away.

For a more comprehensive and detailed understanding of the invention reference may be had to the accompanying drawings in which like reference characters refer to like parts throughout the drawings. Reference character 10 indicates a fuse box having a door 11 hingedly related thereto as at 12. Within the fuse box 11 and secured to the rear wall 13 thereof is insulating block 14 having contacting plates 15, 16, fuse plug 17 and terminal posts 18, 19, as is usual

in such devices. The service wire supporting arm 20, which may be made of any insulating material, preferably wood, has contacting members 21, 22 extending beyond the inner end thereof, which members 21, 22 terminate in circular or ring-like portions 23, 24, which lie at substantially right angles to the service wire supporting arm, and are adapted to encircle the heads of binding screws 25, 26 and contact with terminal posts 18, 19 with their lower faces or bottoms. Service wire supporting arm 20 has groove 27 extending from the inner end of the arm to a point beyond the outer edge 28 of ferrule 29, thereby forming a passageway through which service wire 30 may be readily threaded. The strands forming wire 30 may be readily threaded. The strands forming wire 30 are separated or split at the inner end of the service wire with one of the strands forming the service wire secured to each of the contacting members 21, 22 by binding screws 31, 32, respectively. The service wire supporting arm 20 is supported by rod 33 of bracket, designated generally by reference character 34. The side members 35, 36 of the U-shaped portion of bracket 34 are provided with openings as at 37, 38 for adjustably receiving therethrough rod 33. Set screw 39 is provided in the head of the U-shaped portion of bracket 34 for securing rod 33 in adjusted vertical position. Adjustable clamp 40 secured to the upper extremity of rod 33 supports and provides means for adjusting supporting arm 20 horizontally. Side member 36 of U-shaped portion of bracket 34 is provided with set screw 41 for securing the connector to the bottom wall of the fuse box. Service wire 30 is provided with socket 42 of the usual construction. In making a connection with an electric system the bottom wall of fuse box 10 is inserted between member 35 of the U-shaped portion of bracket 34 and the inner end of set screw 41 with the ring-like portion 23, 24 of contacting members 21, 22 encircling screw heads 25, 26 with the bottom faces of the ring-like portions contacting with terminal posts 18, 19 and the connector secured in position with relation to fuse box 10 by the operation of set screw 41 which co-operates with arm 35 to form a clamp for securing the connector to the bottom wall of the fuse box.

The invention is particularly adaptable

for taking an electric current from fuse boxes such as are commonly found in apartment houses when it is desired to use the current for a purpose other than that which the electric system contemplates, such for example, as the running of a washing machine or the like. The device is so constructed that the current will be taken from the main wires of the system and can therefore be subjected to heavy load without endangering the system.

I claim:

1. A connector for electric wires comprising a bracket, a wire supporting arm carried by the bracket, contacting members carried by the arm, and means for adjusting the contacting members with relation to the terminal posts of an insulating plate within a fuse box.
2. A connector for electric wires comprising a bracket, a wire supporting arm carried by the bracket, contacting members carried by the arm, means for adjusting the contacting members with relation to the terminal posts of an insulating plate within a fuse box, and means for securing the connector to the fuse box.
3. A connector for electric wires comprising an arm, contacting members carried by said arm, means for supporting said arm, means for adjusting the contacting members on said supporting means with relation to the terminal post of an insulating plate within a fuse box, and means for detachably clamping the connector to the wall of the fuse box.
4. A connector for electric wires comprising a bracket, contacting members carried by said bracket, means for adjusting the

contacting members with relation to the 40 terminals posts of an insulating plate within a fuse box, and means for adjustably securing the connector to a fuse box.

5. A connector for electric wires comprising a bracket, a wire supporting arm carried by the bracket, contacting members carried by the arm, means for adjusting the contacting members with relation to the terminal posts of an insulating plate within a fuse box, and means for adjustably securing the connector to a fuse box.

6. A connector for electric wires comprising a bracket, a wire supporting arm having a groove therein, a ferrule surrounding the arm and a portion of the groove, contacting members carried by the arm, means for securing the split ends of a service wire to the contacting members, and means for securing the connector to the wall of a fuse box.

7. A connector for electric wires comprising a bracket, a wire supporting arm carried by the bracket, contacting members carried by the arm, means for securing the bracket to a fuse box, and means for adjusting the contacting members vertically and horizontally.

8. A connector for electric wires comprising a bracket having a U-shaped portion, a supporting rod adjustably related to the 70 U-shaped portion, a set screw extending between the side members of the U-shaped portion, and a wire supporting arm adjustably related to the supporting rod.

In testimony whereof I have signed my 75 name to this specification, on this 15th day of March A. D. 1922.

GUSTAVE M. BOREN.
